Inventor
Paul Held

By *Cad Snow & Co.*

Attorneys.

UNITED STATES PATENT OFFICE.

PAUL HELD, OF ST. CLOUD, MINNESOTA.

SLIDE.

Application filed May 4, 1925 Serial No. 27,978.

To all whom it may concern:

Be it known that I, PAUL HELD, a citizen of the United States, residing at St. Cloud, in the county of Benton and State of Minnesota, have invented a new and useful Slide, of which the following is a specification.

This invention relates to a novel form of trackway especially designed for use in connection with water coasters or toboggans, 10 the primary object of the invention being to provide a trackway including safety rails on which the coaster or toboggan may run, should the coaster or toboggan move from the main track section on its passage over 15 the trackway.

An important object of the invention is the provision of a trackway which may be adjusted vertically, eliminating the necessity of moving the main or body portion of 20 the supports, in order to make the necessary adjustments for the maintenance of the track rails in proper parallel relation with each other, due consideration being given to the strength and durability of the trackway.

25 A further object of the invention is the provision of means whereby the height and inclination of the trackway may be changed to facilitate the use of the trackway with varying tide and water conditions.

30 With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

40 Referring to the drawings:

Figure 1 is a side elevational view of a trackway constructed in accordance with the invention.

45 Figure 2 is a sectional view taken on line 2-2 of Figure 1.

Figure 3 is a fragmental view of one section of the track, the same being shown in perspective.

50 Figure 4 is a longitudinal sectional view through one of the adjustable supports.

Figure 5 is a perspective view of the adjusting member.

Figure 6 is a perspective view of the tubular member in which the adjusting member 55 operates.

Figure 7 is a sectional view taken on line 7-7 of Figure 4.

Referring to the drawings in detail, the trackway is indicated generally by the reference character 5 and is shown as having its lower end disposed in a plane substantially on a level with the water onto which the toboggan not shown, and which moves over the trackway, passes as it leaves the track- 65 way.

The upper end of the trackway 5 is supported by the platform 6, which in turn is supported by the frame work 7 including horizontal bars 8 on which the supporting 70 beams 9 of the platform are secured.

Securing members 10 are mounted on the bars 8 and are secured to the beams 9 by means of the bolts 11 that pass through the securing members and beams. Extending 75 upwardly from the platform are spaced ears 12 that cooperate with the depending ears 13 formed at the ends of the bar 14 which is secured to the upper ends of the angle bars and flat bars forming the supporting members of the trackway, so that the upper end of the trackway will be pivotally supported for vertical adjustment but held rigid 80 against movement longitudinally of the platform.

85 The trackway comprises angle bars 15 that are arranged to provide the lateral supporting members for the track proper between which angle bars are positioned the relatively flat bars 16, which bars are as shown, 90 spaced apart, there being provided a bar 17 for positioning between the flat bars 16, the bar 17 being of a thickness to provide shoulders to prevent the wheels of a toboggan or coaster moving over the trackway from moving laterally, should the wheels thereof jump the main track and attempt to pass laterally clear of the safety rails to be hereinafter more fully described.

100 The main rails of the track are indicated at 18 and are formed preferably of channel bars, the same being bolted or otherwise secured to the angle bars 15, as shown by Figure 3 of the drawings.

Angle irons 19 are bolted to the angle 105 bars 15 and act as supports for the angle

- bars 20 that present upwardly extended flanges constituting safety rails extending at opposite side of the trackway, so that should the coaster or toboggan employed in connection with the trackway move laterally from the main rails 18, the outer wheels will run on the safety rails 20, while the inner wheels will run on the flat bar 16 directly thereunder.
- 10 As illustrated by Figure 1, the trackway is pivotally supported on the platform, so that the same may be moved vertically with its supports, which supports include tubular lower sections 22 and upper threaded sections 23. Fitted in the upper end of each lower section 22 is a bearing member 24 in which the adjusting sleeve 25 operates, the adjusting sleeve being formed with internal spaced teeth 25' designed to cooperate with the threads 26 of the upper section associated therewith.
- 15
- 20

The upper extremity of each section 26 is flattened as at 26' and is provided with an opening 27' for the reception of the bolts 28' that also extend through the ears 29' depending from the trackway, to pivotally connect the sections 26 to the trackway. In order that the adjusting sleeves 25 will be held against upward movement, lugs 27 are provided adjacent to the lower ends thereof, which lugs move in the key-ways 28 of the bearing members 24 and when properly positioned, lie under the lower ends of the bearing members 24 as shown by Figure 4.

35 The upper section of each support is also formed with a longitudinal groove 28, to the end that should it be desired to remove the upper sections, the upper sections may be rotated until the grooves fall opposite the spaced teeth 25' whereupon the upper sections may be lifted.

40 From the foregoing it will be obvious that by rotating the adjusting members 25, the trackway may be adjusted vertically throughout its length. In order that the

trackway will be braced against creeping, horizontal bracing bars 29 are provided, which are shown as connecting adjacent supporting members of the trackway.

45 Steps indicated at 30 may be provided so that persons may pass from the water after they have glided over the trackway on a toboggan or coaster, to again seat themselves for another ride over the trackway.

50 Flanges 31 are formed on the adjusting members 25 and afford means whereby a wrench or other suitable tool may be positioned thereon to rotate the adjusting members 25 to accomplish the adjusting feature.

55 From the foregoing detail description, it is believed that a further detail description as to the operation of the device is unnecessary.

I claim:—

1. A trackway including main rails and safety rails, a platform for supporting one end of the trackway, means for pivotally connecting the trackway to the platform, vertically adjustable supports mounted under the trackway and arranged in spaced relation with each other throughout the length of the trackway, means for adjusting the supports vertically, and means for pivotally connecting the supports to the trackway.

2. A trackway including main rails and safety rails, a platform for supporting one end of the trackway, means for pivotally connecting the trackway to the platform, vertically adjustable supports pivotally connected with the trackway, each of said supports including a hollow lower section, a bearing member in each hollow section, an adjusting member operating in the bearing member, a threaded section operating through the adjusting member, and means for pivotally connecting the supports to the trackway.

60 In testimony that I claim the foregoing as my own, I have hereto affixed my signature.

PAUL HELD.
